COMBINATION TOOL

Filed Aug. 4, 1922

UNITED STATES PATENT OFFICE

JOHN T. SWEENEY, OF KINGSTON, NEW YORK

COMBINATION TOOL

Application filed August 4, 1922. Serial No. 579,588.

My invention relates to combination tools, and more particularly to a household tool embodying therein a cutting blade adapted for use in opening ordinary tin cans, and 5 being so constructed as to remove so-called friction tops from containers of different types, as well as the closure caps from bottles.

A tool embodying my invention is made 10 principally of sheet metal, and embodies a looped handle carrying the cutting blade and a fulcrum head plate secured to the end of the handle above the blade in a manner to present an edge of the metal against the 15 edge of a can so as to avoid any slippage during the cutting movement of the blade, while insuring the desired angular movement of the head during the cutting for the desired long shearing action of the blade.

20 This fulcrum head plate has an angular laterally reduced portion formed integrally therewith, which may be used advantageously for lifting the top from a can of the friction top type, and also for removing the 25 ordinary crown caps from bottles. I also employ a blade having a serrated cutting edge, so as to ensure greater ease in the actuation of the tool when cutting the tin of cans.

30 The invention consists primarily in a combination tool embodying therein a looped handle formed of strip metal, having a portion adjacent its ends closed together, a cutting blade secured between the portion of 35 said handle adjacent the closed ends of the strip forming the same, with its cutting edge projected forwardly thereof, the ends of the handle-forming strip being cut obliquely to the cutting edge of said blade, and a fulcrum head plate permanently secured 40 against the oblique ends of the handle-forming strip above and extending laterally of said cutting blade; and in such other novel features of construction and combination 45 of parts as are hereinafter set forth and described, and more particularly pointed out in the claims hereto appended.

Referring to the drawings,

Fig. 1 is a perspective view of a tool embodying my invention;

Fig. 2 is a side view thereof; Fig. 3 is a section on the line 3—3 of Fig. 2; and

Fig. 4 is a detail view of the fulcrum head plate removed from the tool.

Like letters refer to like parts throughout the several views.

In the embodiment of my invention shown in the drawings, the tool includes a strip metal handle *a* looped intermediate its ends to form the desired grip and at the same time to receive a corkscrew *b* in a protected position where it cannot injure the hand while the tool is in use in opening cans or bottles. This general arrangement 55 is old in the art, being common to many types of can openers.

The strip forming the handle *a* is so formed that the portions thereof adjacent the opposite ends of the strip are contracted 60 as indicated at *c*, space being allowed to receive a cutting blade *d* adjacent the portions of the strip so brought together, which blade is riveted or otherwise secured in position.

The point of the blade *d* projects forwardly of the ends of the strip forming the handle *a*.

Beyond the point of support for the cutting blade, but adjacent thereto, the ends of the strip forming the handle *a* are brought together as indicated at *e*, so as to form a rigid mount for a fulcrum head plate, which will be more fully described hereinafter.

The opposite ends of the strip forming the handle *a* are cut obliquely to the cutting edge of the blade *d* as shown more particularly in Fig. 2, so as to give the desired angular relation of the fulcrum head plate to the cutting edge of the blade *d*, and insure the initial engagement of one edge of this plate with the rim of the can when the cutting blade is in use, towards the beginning of the making of a cut, and of the other edge thereof, towards the end of the making of the cut. The fulcrum head plate is positioned rearwardly of the point of the blade *d* so that said plate will not interfere with the initial puncturing of the metal of a can.

The fulcrum head plate above referred to, 100

is formed of sheet metal having a widened portion *f* at one end thereof, and a narrow angular portion *g* at the other end thereof, the central part of the portion *f* having an 5 arched or curved cutout portion *h*, the center of which arched or curved cutout portion is directly above the cutting blade *d*. The angular portion *g* extends towards the looped handle *a*.

10 Preferably the fulcrum head plate is secured to the handle *a* by means of an angular opening therein indicated at *i* in Fig. 4, adapted to receive angular rivet-forming studs projecting from the ends of the strip 15 forming the handle *a*, these ends being upset by an ordinary riveting operation when assembling the fulcrum head plate in the tool.

10 Preferably the sharpened edge of the cutter *d* is serrated as indicated at *d'*, although other styles of cutting edges may be employed.

In forming the arched or curved cutout portion *h*, in the fulcrum head plate, I use 25 a tool which will remove the metal by a substantially straight cut, thus insuring clean, sharp edges which by reason of the angular position of the fulcrum head plate will be alternately directed against the metal 30 of a can as the cutting of the metal progresses, one edge engaging the can when the position of the tool is such as is required to give the initial cutting action for a long cut, and the other edge engaging the can 35 towards the end of the cut. The bite secured by such edges, particularly that last to engage the can, materially increases the effectiveness of the blade *d*, since any slippage which will occur in the use of a can 40 opener employing a cutting blade of this general type, is greatest towards the end of the upward movement of the blade when making the cut.

The rivet-forming studs are indicated at 45 *i'* and the part of the narrow angular portion *g* used for removing friction tops or bottle caps is indicated at *g'*, this part having a reduced edge as shown and being of a length to secure the necessary leverage 50 against the edge of a can adjacent the rim of a friction top in removing such a top, the handle *a* providing a fulcrum securing the leverage necessary for removing a crown bottle cap.

55 In assembling the tool, the studs *i'* are passed through the angular opening *i* in the fulcrum head plate, and are riveted in the usual manner, the angularity of the opening *i* preventing rotative movement of said 60 plate with relation to the handle, and the oblique ends of the strip forming the handle *a*, giving the desired inclination to the plate, the riveting being sufficiently strong to insure the necessary permanency in the 65 positioning of this plate with relation to

the blade *d*. This plate is assembled in the structure after the blade *d* has been secured to the handle, it being possible to mount the corkscrew *b* either before or after the attachment of the fulcrum head plate.

When using the tool as a can opener, the top or the side of a tin can is punctured by the blade with a blow upon the end of the handle of sufficient force to cause 70 the point of the blade *d* to pass through the tin. The blade is then forced downwardly and forwardly and brought for a substantial portion of its length beneath the tin to be cut. This causes the edge of the cutout portion *h* positioned toward the handle *a* to

75 engage the metal of the can so as to bite thereon in a manner to facilitate the initial upward movement of the blade without possibility of slippage. During this upward movement, and immediately following the 80 initial cutting action, the angle of the blade *d* will be such as to minimize any tendency of the fulcrum head plate to slip and prevent cutting action of the blade, but as the angle of the blade becomes more acute, the 85 tendency of the fulcrum head to slip is very much accentuated.

By mounting the fulcrum head plate at an angle, however, the engagement of the forward edge thereof with the can in the direction of the cut, is delayed so that the final oscillatory movement of the tool will be about this edge as a fulcrum so that the strongest bite is secured at that time toward the end of the cut when the tendency of the resistance encountered by the blade is to cause slippage of the fulcrum head in relation to the can.

The arched or curved cutout portion *h* is that commonly found in can openers, to provide side guides or gages facilitating the 105 use of the cutter about either the edge of the top of a can or the side of the can adjacent the top.

The construction of the fulcrum head plate and its oblique position with relation 110 to the edge of the cutting blade imparts particularly desirable characteristics to the tool both in insuring more effective accuracy of the tool when cutting and insuring economy in production.

115 It is not my intention to limit the invention to the precise details of construction shown in the drawings, it being apparent that such may be varied without departing from the spirit and scope of the invention.

Having described the invention, what I claim as new and desire to have protected by Letters Patent, is:—

120 1. A tool of the character described embodying therein a looped handle formed of strip metal, having a portion adjacent its ends closed together, whereby a cutting blade may be secured between the portion 125 of said handle adjacent the closed ends of the strip forming the same, with its cutting 130

edge projected forwardly thereof, the ends of the handle-forming strip being cut obliquely, and a fulcrum head plate permanently secured against the oblique ends of the handle-forming strip above and extending laterally of the closed ends of said handle.

2. A tool of the character described embodying therein a handle, a metal plate secured intermediate its ends to the end of said handle, said plate having one end thereof laterally extended and provided substantially centrally of the edge thereof with a curved cutout portion, and the other end thereof laterally reduced with its extremity turned at an angle longitudinally of and projecting towards the handle.

3. A tool of the character described embodying therein a looped strip metal handle having its ends closed together, and cut obliquely, a metal plate secured intermediate its ends to the end of said handle, said plate having one end thereof laterally extended and provided substantially centrally of the edge thereof with a curved cutout portion, and the other end thereof laterally reduced with its extremity turned at an angle longitudinally of and projecting towards the handle, and means permanently securing said plate against the oblique ends of the handle-forming strip.

4. A tool of the character described embodying therein a looped handle formed of strip metal, having a portion adjacent its ends closed together whereby, a cutting blade may be secured between the portion of said handle adjacent the closed ends of the strip forming the same, with its cutting edge projected forwardly thereof, the ends of the handle-forming strip being cut obliquely, and having rivet-forming studs formed integrally therewith and projecting therefrom, and a fulcrum head plate having an angular opening through which said studs are passed and upset, whereby said plate is permanently secured against the oblique ends of the handle-forming strip above and extending laterally of the closed ends of said handle.

5. A tool of the character described embodying therein a looped strip metal handle having its ends closed together, and cut obliquely, a metal plate secured intermediate its ends to the end of said handle, said plate having one end thereof laterally extended and provided substantially centrally of the edge thereof with a curved cutout portion, and the other end thereof laterally reduced with its extremity turned at an angle longitudinally of and projecting towards the handle, and rivet-forming studs formed integrally with and projecting from the ends of the strip forming the handle, said plate having an angular opening there-through adapted to receive said studs and

said studs being of a length to be upset against said plate to permanently secure it against the oblique ends of the handle-forming strip.

In witness whereof I have hereunto affixed my signature, this 20th day of July, 1922.

JOHN T. SWEENEY.
